UNITED STATES PATENT OFFICE.

JEROME A. HOUSTON, OF SPRINGFIELD, MISSOURI.

STOP-PIN FOR COUPLING-HEADS.

1,111,154.

Specification of Letters Patent. Patented Sept. 22, 1914.

Application filed March 21, 1914. Serial No. 826,276.

To all whom it may concern:

Be it known that I, JEROME ADOLPH HOUSTON, a citizen of the United States, residing at Springfield, in the county of 5 Greene and State of Missouri, have invented certain new and useful Improvements in Stop-Pins for Coupling-Heads, of which the following is a specification, reference being had to the accompanying drawings.

10 This invention relates to new and useful improvements in coupling devices and more particularly to air brake hose coupling.

The main object of the invention is the provision of means whereby the usual stop pin upon the coupling member is replaced after the same has been broken off of the coupling head so as to render the head useful instead of discarding the same.

Another object of the invention is the provision of a device of the above character which will possess advantages in points of efficiency and durability, is inexpensive to manufacture, and at the same time is simple in construction and operation.

25 With the above and other objects in view, the invention consists in the novel features of construction and the combination and arrangement of parts to be hereinafter more fully described, claimed and pointed out in 30 the accompanying drawings, in which—

Figure 1 is a bottom plan of a coupling head, the original retaining pin being shown partly broken away and illustrated in dotted lines. Fig. 2 is a similar view, parts being 35 shown in section and my improved substitute pin arranged in its effective position; and Fig. 3 is a detail perspective view of the pin before being engaged with the coupler head.

40 In the accompanying drawings I have illustrated in Fig. 1 a coupling head which is especially adapted for use upon air brake hose, said coupling head being of the usual form and provided with a stop pin 1 which 45 extends transversely between the main body of the coupling head, and the arm 2. It is a well known fact that after the stop pins 1 become broken, it renders the coupling head useless and thus necessitates the discarding 50 of the same. As explained above it is the main object of my invention to replace this stop pin by a new one which will render the coupling head useful and at the same time will be effective and strong as a new head.

55 In placing the coupling head in shape for the receiving of the new pin, the arm 2 is

ground down upon the outer side as shown at 3 to provide the outwardly projecting ear 4, said ear being provided with a transverse opening 5 which is adapted to receive 60 the hook portion 6 formed upon one end of the substitute rod 7. This substitute rod is formed of a material similar to the material of which the coupling head is formed and when in its operative position will be disposed transversely between the arm 2 and the body member of the coupling head.

65 It will be noticed that in Fig. 1 the inner end of the pin 1 is formed integral with an outwardly projecting boss 8 and after the 70 pin 1 has been broken, an opening 9 is driven through this boss to receive the end of the rod 7 opposite the hook 6. After this end has been inserted through the opening 9 it is bent inwardly upon the boss as shown at 75 10 and as the hook member 6 is bent in a direction opposite the hook 10, the rod 7 will be securely held against any longitudinal movement by means of these hooks. It will be apparent from the foregoing that 80 the rod 7 may be quickly and readily engaged with the coupling head after the openings have been drilled within the ear 5 and the boss 8. It will be noted that the rod when formed will be provided upon one end 85 with a hook 6 while the other end thereof is straight and in placing the same in position, the straight end thereof is inserted within the opening 9 of the boss 8 and the hook 6 is engaged with the perforated ear 5. 90 After the hook 6 and the straight end of the rod are in their effective positions, the end of the rod is bent inwardly upon the boss as shown at 10. Thus it will be seen that the rod 7 will be securely retained in its operative 95 position as illustrated in Fig. 1. From this it will be apparent that a great saving is brought about by replacing the stop pins 1 instead of discarding the coupling head after this pin has been broken off. In view 100 of the fact that the breaking of this stop pin will render the coupling head useless, the necessity of a new stop pin will be readily apparent.

105 My device as herein shown and described is extremely simple in construction, can be quickly and readily applied to any form of coupling head, and at the same time can be manufactured and placed upon the market at a comparatively small cost.

110 While I have shown and described the preferred form of my invention, it will be

obvious that various changes in the details of construction and in the proportions may be resorted to for successfully carrying my invention into practise without sacrificing 5 any of the novel features or departing from the scope of the appended claims.

What I claim is:—

The combination with a coupling head having a perforated ear and a boss provided 10 with an opening, of a pin having a hook formed at one end and adapted to engage with the perforated ear, said hook portion being disposed in parallel relation with the

body of the pin, the other end of said pin extending through the opening in the boss 15 and bent upon the boss to securely retain the pin against movement, said end being bent in a direction opposite to the direction in which the hook extends, so as to securely retain the pin in its effective position. 20

In testimony whereof I hereunto affix my signature in the presence of two witnesses.

JEROME A. HOUSTON.
